DESIGN FOR A HOUSE COAT

Paige Salfeety, New York, N. Y.

Application July 21, 1942, Serial No. 107,640

Term of patent 7 years

To all whom it may concern:

Be it known that I, Paige Salfeety, a subject of the King of Great Britain, residing in New York city, county of New York, and State of New York, have invented a new, original, and ornamental Design for a House Coat, of which the following is a specification, reference being had to the accompanying drawing, forming part thereof, wherein,

Figure 3 is a front view of the house coat, drawn on a smaller scale, showing the garment in an open position with the belt removed.

I claim:

The ornamental design for a house coat, substantially as shown and described.

PAIGE SALFEETY,
